UNITED STATES PATENT OFFICE.

GEORGE W. CROWLEY, OF PHILADELPHIA, PENNSYLVANIA, ASSIGNOR OF FORTY-NINE ONE-HUNDREDTHS TO JOHN T. GREEN, OF PHILADELPHIA, PENNSYLVANIA.

DESIGN FOR A CAP FOR TYPE-WRITING-MACHINE KEYS.

46,020.

Specification for Design.

Patented June 30, 1914.

Application filed March 13, 1914. Serial No. 824,559. Term of patent 14 years.

To all whom it may concern:

Be it known that I, GEORGE W. CROWLEY, a citizen of the United States, residing at the city of Philadelphia, in the county of Philadelphia and State of Pennsylvania, have invented a new, original, and ornamental Design of a Cap for a Type-Writing-Machine Key, of which the following is a specification, reference being had to the accompanying drawing, illustrating, perspectively, the constructive detail arrangement of the cap for a type-writing-machine key of my new design.

The hollow cap of my particular design in tubular form is provided as a part of the top with an integral circular raised back having inclined edges extending to the body of the top of said cap.

I claim:—

The ornamental design of a cap for a typewriting machine key, as shown and described.

GEO. W. CROWLEY.
